Inventor
Joshua A. Dill

UNITED STATES PATENT OFFICE.

JOSHUA ADAM DILL OF FREDERICK, MARYLAND.

LIFTING-JACK.

SPECIFICATION forming part of Letters Patent No. 363,050, dated May 17, 1887.

Application filed March 14, 1887. Serial No. 230,863. (No model.)

To all whom it may concern:

Be it known that I, JOSHUA ADAM DILL, a citizen of the United States, residing at Frederick, in the county of Frederick and State of Maryland, have invented a new and useful Improvement in Lifting-Jacks, of which the following is a specification.

My invention relates to an improvement in lifting-jacks for vehicles; and it consists in the peculiar construction and combination of devices, that will be more fully set forth hereinafter, and particularly pointed out in the claims.

In the drawings, Figure 1 is a perspective view of a lifting-jack embodying my improvements. Fig. 2 is a side view of the same in another position. Fig. 3 is a horizontal sectional view taken on the line *x x* of Fig. 2. Fig. 4 is a similar section on the line *y y*, Fig. 2.

A represents a vertical standard, which is provided at its lower end with a supporting-base, B. To the upper end of the standard, on opposite sides thereof, are secured plates C, which extend above the upper end of the standard and form ears, between which is pivoted an operating-lever, D. On the front edge of the standard, at a suitable distance from the lower end thereof, is a series of ratchet-teeth, E.

F represents a vertically-movable bar, which is arranged on one side of the standard A, and is provided near its upper end with an arm, G, which extends rearwardly across one side of the standard A, and has its rear end bent inward at right angles and caused to engage a vertical slot, H, which is made in one side of the standard. A vertical slot, I, is made on the front edge of one of the plates C, to permit the arm G to extend between the same and the opposing side of the standard. Near the lower end of the bar F, on the inner edge thereof, is a series of ratchet-teeth, K, which are adapted to engage the ratchet-teeth E of the standard when the said bar is elevated.

M represents a foot-bar, which is attached to the lower end of the bar F and extends transversely across the standard A, the said foot-bar being provided with a vertical opening, through which the said standard passes. The upper end of the bar F is connected to the short

end of the lever D by means of links N. On 50 the front edge of the bar F, at a suitable distance from the lower end thereof, is a vertical series of ratchet-teeth, O.

P represents a bracket, which has its rear end bifurcated to receive the bar F, and from 55 the lower side of the said bracket depends a detent, R, which forms a pawl and is adapted to engage the ratchet-teeth O.

S represents a pin, which connects the bifurcated rear end of the bracket and extends 60 across the rear side of the bar F, and works in a vertical groove or recess, T, with which the said bar is provided.

A flat spring, U, is secured to the inner edge of the standard A, and extends outwardly toward the opposing inner edge of the bar F and bears against the said bar, the function of the said spring being to normally move the bar F a slight distance from the standard A, so as to prevent the ratchets K from engaging the 70 ratchet-teeth E.

The operation of my invention is as follows: In order to raise one end of the axle of a vehicle to remove the wheel therefrom, the operator inserts the front end of the bracket P 75 under the said axle, having previously raised the bracket to a suitable point on the bar F. He then bears down on the free end of the lever D, which causes the bar F to rise and carry the bracket with it, and thus raise the axle of 80 the vehicle. The weight of the vehicle causes the bar F to move toward the standard A against the pressure of the spring U, so that when the bar F has been raised a suitable distance its ratchet-teeth K become engaged with 85 the ratchet-teeth E on the standard, and thus the bar F is locked in position and holds the axle of the vehicle when elevated. In order to lower the axle, the operator places one foot on the outer end of the foot-bar M, thereby causing the lower end of the bar F to 90 recede from the standard A and disengage its teeth from the teeth of the said standard, when the lever D is free to move upwardly and cause the bar F and the bracket to descend.

By providing the vertically-moving bar F with the ratchet-teeth O, and the vertically-movable bracket P having the detent to en-

gage the said teeth, the said bracket may be adjusted to the necessary height on the bar F in a very short space of time.

Having thus described my invention, I 5 claim—

1. In a lifting-jack, the combination of the standard having the teeth E, the lifting-bar movable vertically and adapted to swing toward and from the standard, and having the teeth 10 K to engage the teeth E, the spring U, to normally move the lifting-bar out of engagement with the standard, and the lever to raise and lower the lifting-bar, substantially as described.

2. The combination, in a lifting-jack, of the 15 vertical standard A, having the ratchet-teeth E on one edge near its lower end, the lever D, fulcrumed to the upper end of the standard, the vertically-movable bar F, connected to the lever and having the teeth K, to engage the 20 teeth of the standard when the bar F is raised,

and the bracket P, secured to the bar F, substantially as described.

3. The combination, in a lifting-jack, of the standard A, having the teeth E near its lower end, the lever D, fulcrumed to the upper end 25 of the standard, the vertically-movable lifting-bar F, connected to the lever and provided at its lower end with the teeth K, adapted to engage the teeth E, (when the bar F is raised,) the foot-bar M, projecting from the bar F, and the spring 30 U, to normally move the lower end of the bar F from the standard A, for the purpose set forth, substantially as described.

In testimony that I claim the foregoing as my own I have hereto affixed my signature in 35 presence of two witnesses.

JOSHUA ADAM DILL.
